UNIVERSAL SHANK BUTTON ATTACHMENT

Larry C. Liero, Anthony A. Arcury, and Paul C.
Trilli, Wind Gap, Pa.

Application May 3, 1951, Serial No. 224,424

13 Claims. (Cl. 112—114)

1

This invention relates to a shank button attachment for button sewers and more particularly to an improved universal attachment that is capable of holding a wide variety of buttons and which may be used either right or left-hand on the standard makes of button sewers.

Heretofore, shank button attachments for button sewers were relatively crude devices which generally speaking, could be used only with one size and type of button and on one particular sewing machine. Furthermore, in many if not all cases, these attachments were so cumbersome and complicated that they could not be switched for selective right or left-hand use. This feature is of especial importance because operators frequently refuse to use a button sewer which is not set up for right or left-hand use at the option of the operator. Not only is it sometimes physically and nervously impossible for a left-handed operator to use a right-hand attachment, but the fact that most button sewing is done on a piece-work basis, it will be seen that operators insist that the sewers be arranged for maximum speed and efficiency.

A primary object of the present invention therefore, is to provide a relatively inexpensive universal shank button attachment for button sewers.

A further object of the invention is to provide a universal shank button attachment for button sewers capable of being attached to the sewing machine for either right or left-hand manipulation.

A further object of the invention is to provide an improved shank button sewing attachment having a specially designed spring-loaded plunger for holding the buttons in position, which facilitates the rapid insertion and removal of the buttons.

A still further object of the invention is to provide a shank button attachment assembly comprising a universal fixture and a slotted bracket adapted to be secured to the fixture in a plurality of positions, thereby enabling the fixture to be mounted as desired on any button sewer.

Further objects will be apparent from the specification and drawings in which:

Fig. 1 is an exploded view in perspective showing the fixture and bracket of our improved shank button attachment;

Fig. 2 is a perspective showing the fixture body of Fig. 1 before assembly;

Fig. 3 is a perspective of a typical shank button used with the present attachment;

Fig. 4 is a top view partly sectioned, of our

2

shank button attachment as mounted for left-hand operation with a button sewer of the Singer 114 class;

Fig. 5 is a sectional view as seen at 5—5 of Fig. 4;

Fig. 6 is a fragmentary detail showing a relatively smaller shank button positioned in the fixture;

Fig. 7 is a perspective of the structure of Fig. 4;

Fig. 8 is similar to Fig. 7 except that the attachment has been set for right-hand operation;

Fig. 9 shows the attachment assembled for left-hand operation on a button sewer such as the Singer 175 class;

Fig. 10 is a top view of the attachment in the position shown in Fig. 9, secured to a button sewer; and

Fig. 11 is similar to Fig. 9 with the attachment adjusted for right-hand operation.

The invention comprises essentially the provision of a button holding fixture having a shank button-receiving aperture formed integrally with an offset housing for a spring-loaded plunger, the centerline of the aperture being substantially in the same horizontal plane and at right angles to the centerline of the plunger. The button aperture portion of the fixture is provided with a plurality of drilled and tapped holes preferably on adjacent edges thereof, to which a slotted bracket may be clamped so that the fixture is supported on the button sewer in the proper manner for sewing buttons to fabric, etc.

Referring now more particularly to the drawings, the fixture proper for holding the shank buttons comprises a rectangular block portion 10 which is formed integrally with the offset plunger housing 11 (as shown clearly in Figs. 1 and 2). The block portion 10 is drilled at 12 and then slotted vertically at 13 to provide an aperture extending substantially halfway across the block 10 which has an enlarged bore for receiving the shank 14 of any conventional shank button such as shown at 15 in Fig. 3. In current practice, the thickness of shank 14 in a plane perpendicular to the centerline of the hole 16 in the shank is substantially constant for buttons varying from the small 12 line size to the large 18 line size, and including the 14 line and 16 line sizes. It is therefore possible to select the diameter for hole 12 in block 10 so that regardless of whether the small 12 line button or the large 18 line button is used, the shank hole 16 of the button is always substantially on the centerline of the hole 12 in the block 10 (as shown in Fig. 4). Even though the diameter of the shank may vary somewhat, it is always possible to position the

hole of the shank so that it clears the sides of slot 13. Furthermore, while there is some variation in the length of shank 14, we mill or cut slot 13 sufficiently deep so that there is always ample clearance between the bottom of the slot and the end of the button shank when in position.

The button 15 regardless of the diameter or size of the button head, is retained in place by means of the convex head 18 of a spring-loaded threaded plunger 19. The tension exerted on the button heads as well as the maximum displacement of the plunger due to the action of spring 20, is adjusted by means of nut 21 which is retained on the plunger by a lock nut 22. Proper adjustment of nut 21 and plunger 19 is such that the buttons 15 may be readily snapped into position (shown in Fig. 4) by the operator and likewise removed with a minimum of effort. The convex shape of head 18 provides a slight component of pressure at right angles to the centerline of the plunger so that a round headed button is forced into and retained in the hole 12 in such a manner that the head of the button is firmly seated against face 23 of block 10. In a similar manner, the shape of the head 18 securely retains a relatively small flat-headed button 15a (Fig. 6) so that the only adjustment necessary in converting the attachment to handle buttons varying as much as those shown in Figs. 3 and 6, is a simple adjustment of the nut 21 to compensate for variations in the diameter of the button head.

The block 10 is provided with a tapped and drilled hole 25 which is in alignment with the centerline of hole 12. A second drilled and tapped hole 26 is provided on the adjacent face 27 which is at right angles to faces 23 and 28 thereof. A special bracket 29 is bolted to either face 27 or 28 by means of machine screw 30. Bracket 29 has two vertical slots 31 and 32 formed between upright arms 33, 34 and 35. Desirably, the lower web 36 of the bracket is thinner than the arms 33-35 so that the shoulders 37 and 38 overlie the top of block 10 to prevent relative turning of the block with regard to the bracket.

It will be apparent that the relative movement of the needle with regard to the fixture must be along the centerline of slot 13, and this applies whether the relative movement is to and from the operator, or back and forth in front of the operator. In either case, the needle 40 alternately penetrates the hole 16 in the button shank 14 and the gap between the end of the button shank and the bottom of slot 13 (Fig. 5). When the attachment is mounted on a machine of the Singer 114 class which oscillates as shown by the double arrow in Fig. 4, the attachment is assembled so that bracket 29 is secured to the fixture by screw 30 in hole 25, and to the arm 41 of the button sewer by means of a machine screw 42 (Figs. 4 and 5). A shoe 43 may be added if desired, to a button sewer of the Singer 114 class to provide the necessary cooperation between the fixture, the needle 40, and the material to which the button is sewed.

Figs. 4, 5 and 7 show the attachment assembled for a left-handed operator. For a right-handed operator, the fixture is reversed on bracket 29 (as shown in Fig. 8). Since the centerline of hole 25 coincides with the centerline of hole 12, the fixture works equally well in either position, there being no displacement of the slot 13 when the fixture is reversed.

When the shank button attachment is used

with a Singer 175 class in which the needle bar vibrates and the button attachment is stationary, or in a machine such as the Lewis button sewer in which the arm carrying the button attachment vibrates crosswise, we merely clamp the bracket 29 to the face 27 of block 10 (as shown in Figs. 9-11). Desirably, the web 36 does not extend completely across the length of the bracket 29 so that the ends of the bracket will be substantially in line with the face 28 of block 10 and the outer face 45 of housing 11.

Figs. 9 and 10 show the attachment assembled for left-hand operation and in this case, the bracket 29 is secured to the sewing machine in slot 31. To reverse the fixture for right-hand operation as shown in Fig. 11, it is necessary to remove screw 30 entirely and reverse bracket 29 so that the attachment is clamped to the sewing machine in the other slot 32. It will be understood that the reference line or axis about which the attachment must be turned in order to obtain equally satisfactory right and left-hand operation, is a line halfway between the two extreme positions 41 and 47 of the needle with respect to the attachment (Fig. 10). Provided the distance from center of screw 42 to the reference line remains constant, the fixture can be reversed without the necessity for further adjustment of the button sewer. Therefore, we locate the centers of slots 31 and 32 equi-distant from the reference line, as shown in Fig. 10, to facilitate reversal. However, it may be desirable to provide limited play between the shank of screw 42 and the sides of the slots 31 and 32 so compensation can be made for slight variations in the reference line which might occur for different styles or sizes of buttons.

It will thus be understood that the fixture proper comprising the body 10 and the plunger housing 11, can be applied either right or left-hand to any style or make of button sewer. With the use of a bracket such as the bracket 29, we have shown specifically how the fixture is applied to the Singer 175 class as well as the Singer 114 class, these two machines being considered typical because in one case the needle bar oscillates and in the other case the button attachment and presser foot oscillate. Also, the paths of movement of the button attachment with regard to the needle are at right angles to each other in these two machines. It will therefore be apparent that the particular features of our fixture render it especially suitable for universal use, not only with regard to the make and model of the machine, but also with regard to a wide range of sizes and styles of shank buttons.

Having thus described our invention, we claim:

1. A shank button attachment for button sewers and the like, comprising a body member, walls in said body member defining a button shank-receiving aperture, walls in said body member defining a needle slot in registry with the button shank aperture, and a spring-loaded plunger mounted in said body, the centerline of the plunger being substantially at right angles to the centerline of the button shank aperture whereby the plunger is positioned to contact the head of a shank button when seated in the aperture.

2. A shank button attachment for button sewers and the like, comprising a body member, walls in said body member defining a button shank-receiving aperture, walls in said body member defining a needle slot in registry with the button shank aperture, a supporting member in registry with the centerline of the button shank aperture

5

and around which the body member may be turned substantially 180°, and a spring-loaded plunger mounted in said body, the centerline of the plunger being substantially at right angles to the centerline of the button shank aperture whereby the plunger is positioned to contact the head of a shank button when seated in the aperture.

3. A shank button attachment for button sewers and the like, comprising a body member, walls in said body member defining a button shank-receiving aperture, walls in said body member defining a needle slot in registry with the button shank aperture, a spring-loaded plunger mounted in said body, the centerline of the plunger being substantially at right angles to the centerline of the button shank aperture whereby the plunger is positioned to contact the head of a shank button when seated in the aperture, and a convex, enlarged head on said plunger.

4. A shank button attachment for button sewers and the like, comprising a body member, walls in said body member defining a button shank-receiving aperture, walls in said body member defining a needle slot in registry with the button shank aperture, a spring-loaded plunger mounted in said body, the centerline of the plunger being substantially at right angles to the centerline of the button shank aperture whereby the plunger is positioned to contact the head of a shank button when seated in the aperture, a convex, enlarged head on said plunger, and means for adjusting the displacement of the plunger with respect to the body.

5. A shank button attachment for button sewers and the like, comprising a body member having two faces at right angles to each other, walls in said body member defining a button shank-receiving aperture, walls in the body member defining a needle slot in registry with the button shank aperture, the depth of the needle slot being substantially greater than the length of a button shank, a bracket by which the body member is secured to a button sewer, and a reversible connection between the bracket and the body member.

6. A shank button attachment for button sewers and the like, comprising a body member having two faces at right angles to each other, walls in said body member defining a button shank-receiving aperture, walls in the body member defining a needle slot in registry with the button shank aperture, the depth of the needle slot being substantially greater than the length of a button shank, a bracket by which the body member is secured to a button sewer, a reversible connection between the bracket and the body member, and a spring-loaded plunger mounted in said body, the centerline of the plunger being substantially at right angles to the centerline of the button shank aperture whereby the plunger is positioned to contact the head of a shank button when seated in the aperture.

7. A shank button attachment for button sewers and the like, comprising a body member having two faces at right angles to each other, walls in said body member defining a button shank-receiving aperture, walls in the body member defining a needle slot in registry with the button shank aperture, the depth of the needle slot being substantially greater than the length of a button shank, a bracket by which the body member is secured to a button sewer, a spring-loaded plunger mounted in said body, the centerline of the plunger being substantially at right angles to the centerline of the button shank aperture

6

whereby the plunger is positioned to contact the head of a shank button when seated in the aperture, and means for connecting the bracket to either of said faces.

5 8. A shank button attachment for button sewers and the like, comprising a body member having two faces at right angles to each other, walls in said body member defining a button shank-receiving aperture, walls in the body member defining a needle slot in registry with the button shank aperture, the depth of the needle slot being substantially greater than the length of a button shank, a bracket by which the body member is secured to a button sewer, a spring-loaded plunger mounted in said body, the centerline of the plunger being substantially at right angles to the centerline of the button shank aperture, and a convex head for said plunger positioned to contact the head of a shank button when seated in the aperture.

20 9. A shank button attachment assembly for button sewers and the like, comprising a body member having two faces at right angles to each other, walls in said body member defining a button shank-receiving aperture, walls in the body member defining a needle slot in registry with the button shank aperture, the depth of the needle slot being substantially greater than the length of a button shank, a spring-loaded plunger mounted in said body, the centerline of the plunger being substantially at right angles to the centerline of the button shank aperture whereby the plunger is positioned to contact the head of a shank button when seated in the aperture, a bracket for selectively clamping the body member to a button sewer, and connecting means operatively associated with the bracket and the body member for selectively positioning the body member for either right or left-hand operation.

30 40 10. A shank button attachment assembly in accordance with claim 9, in which the connecting means is substantially in line with the centerline of the needle slot.

45 11. A shank button attachment assembly in accordance with claim 9, in which the connecting means is offset with respect to a reference line at right angles to the centerline of the needle slot and substantially bisecting the amplitude of relative movement between the button attachment and the needle.

50 12. A shank button attachment assembly for button sewers and the like, comprising a body member having two faces at right angles to each other, walls in said body member defining a button shank-receiving aperture, walls in the body member defining a needle slot in registry with the button shank aperture, the depth of the needle slot being substantially greater than the length of a button shank, a spring-loaded plunger mounted in said body, the centerline of the plunger being substantially at right angles to the centerline of the button shank aperture whereby the plunger is positioned to contact the head of a shank button when seated in the aperture, a slotted bracket for selectively clamping the body member to a button sewer, and connecting means operatively associated with the bracket and the body member for selectively positioning the body member for either right or left-hand operation.

60 65 70 75 13. A shank button attachment assembly for button sewers and the like, comprising a body member having two faces at right angles to each other, walls in said body member defining a button shank-receiving aperture, walls in the body

member defining a needle slot in registry with the button shank aperture, the depth of the needle slot being substantially greater than the length of a button shank, a spring-loaded plunger mounted in said body, the centerline of the plunger being substantially at right angles to the centerline of the button shank aperture whereby the plunger is positioned to contact the head of a shank button when seated in the aperture, a bracket for selectively clamping the body member to a button sewer, walls defining at least two parallel slots in said bracket, the centerlines of said slots being located substantially equi-distant from a reference line at right angles to the needle slots and substantially bisecting the amplitude of relative movement between the button attachment and the needle, and connecting means operatively associated with the bracket and the body member for se-

lectively positioning the body member for both right and left-hand operation from either of said slots.
